United States Patent

Des. 238,174
Patented Dec. 23, 1975

238,174

DENTAL TOOL

Roger B. Felt, Layton, Utah, assignor to Perma-
Technological Industries, Inc., Ogden, Utah

Filed Nov. 19, 1973, Ser. No. 417,451

Term of patent 14 years

Int. Cl. D24—02

U.S. Cl. D24—1 D

FIG. 1 is a side elevational view of a dental tool showing my new design;

FIG. 2 is a fragmentary perspective view of the upper end thereof;

FIG. 3 is a fragmentary perspective view of the lower end thereof; and

FIG. 4 is a cross section along lines 4—4 of FIG. 1.
I claim:

The ornamental design for a dental tool, substantially as shown.
